UNITED STATES PATENT OFFICE.

WILLIAM H. WOERHEIDE, OF ST. LOUIS, MISSOURI.

CLEAT FOR SECURING PREPARED ROOFING.

973,902.

Specification of Letters Patent.

Patented Oct. 25, 1910.

Application filed January 22, 1909. Serial No. 473,710.

To all whom it may concern:
Be it known that I, WILLIAM H. WOERHEIDE, a citizen of the United States of America, residing in the city of St. Louis and State of Missouri, have invented certain new and useful Improvements in Cleats for Securing Prepared Roofing, of which the following is a full, clear, and exact description, reference being had to the accompanying drawings, forming part of this specification.

My invention relates to a cleat for use in securing sheets of prepared roofing upon buildings and used in lieu of means ordinarily employed in securing such roofing sheets, such for instance as, large headed nails and cement, or nails and cement used in conjunction with the ordinary round caps of metal through which the nails are driven and which rest upon the roofing sheets.

There are many objections to the use of nails alone or nails in association with metal caps in attaching roofing sheets to buildings among which objections the following may be enumerated: Large headed nails, or round metal caps used in conjunction with common nails, provide only very small bearing surfaces and as they are usually placed on from two inch to four inch centers (or two to four inches apart) it is quite obvious that they bind but a very small percentage of the seam or lap, in comparison with the space between nails (or metal caps and nails) where the roofing sheets are not secured at all, and as prepared roofing fabrics generally have a tendency to buckle up, especially between nailing points, it is apparent that these accessories do not provide for a water-tight seam of continuous and uniform pressure. This small and intermittent bearing surface also permits the nails to pull through and tear the roofing fabric when it is subjected to wind pressure or to the strain of expansion and contraction of buildings during the extremes of heat and cold. It is also very difficult, in fact practically impossible, to prevent workmen from canting large headed nails, resulting in the heads cutting into and very often through the roofing fabric, resulting in leaks, and assisting in creating and furthering troublesome conditions.

As all prepared roofing is lapped before being nailed, it is apparent that nails are placed without regard to cracks or spaces beneath the roofing material where sheathing

boards abut, therefore a great many nails are driven into these cracks, and as each nail, or metal cap and nail forms a separate and perfectly independent part of the general fastening scheme, it is clear that all nails so driven into cracks, lose at once and entirely their efficiency and eventually work out, not only leaving a hole directly through both sheets of roofing fabric (through which water enters,) but also permitting the lap to open for a space of from four to six inches.

All of the accessories in use at the present time for securing prepared roofing, are dependent upon a semifluid, so called, roofing cement, which in theory is calculated to thoroughly cement adjoining sheets of roofing fabric where they overlap. However, this cement does not in actual practice do what theory claims for it as it is invariably applied cold, and since it takes from twenty-four to thirty-six hours to set, it can be readily appreciated that where there is no pressure brought to bear between the nailing points this cement is in nowise effective in securing the seam between the fastening points. Furthermore, the use of cement with prepared roofing is not only inconvenient and uncertain, but detracts materially from the ornate appearance of the roof of a building.

It is the object of my invention to provide a cleat which will insure an absolutely watertight seam of continuous and uniform strength and pressure, without the use of cement, and whereby prepared roofing fabrics may be firmly and unyieldingly held in place, and so retained throughout their extent upon the roof as to overcome completely the objectionable occurrences and features to which I have directed attention.

Figure I is a sectional perspective view of the roof of a building showing prepared roofing thereon secured at the butt and seams with my improved cleats. Fig. II is an enlarged longitudinal section taken through one of my cleats and through a fragment of a roof. Fig. III is an enlarged cross section taken through one of my cleats and through a fragment of a roof.

In the accompanying drawings, A designates a fragment of sheathing of a roof and B roofing sheets laid upon the sheathing and overlapped to provide seam joints. The roofing sheets are shown in Fig. I as extending in a vertical direction only, but it is ob-

vious that they may be extended in a horizontal direction equally as well.

1 designates my cleats, which are made of a stiff sheet metal and are arched transversely. Each cleat is also bowed or curved downwardly at its ends, as seen at 2. The sides and ends of the cleat are provided with a continuous outwardly projecting base flange 3, which is provided so that the cleat may rest upon the fabric or roofing in such a manner as to permit of a strong and continuous binding pressure being brought to bear without injuring or impairing the roofing fabric and also in such a manner that the strain of holding a tight seam does not bear directly at nailing points, but by the shape of my cleat and the flange the strain of holding a seam tight is evenly distributed throughout the length of the seam.

20 My cleat is provided with a plurality of nail holes located in a line extending longitudinally of the cleat and midway of its sides, through which the nails, as seen at 4, may be driven to hold the cleat in place upon the roofing sheet.

25 In the use of my roofing cleats the flanges of the cleats press firmly upon the fabric by which the cleats are held and when the nails are driven through the cleats, roofing fabric and the sheathing beneath the roofing fabric, the cleats are held solidly in position.

30 I desire to direct particular notice to the fact that even though some fastening nails driven through my cleat should pass into cracks or crevices in or between the sheathing boards of the roof there are always other nails in position in the cleat which are solidly embedded in the sheathing and act to hold the cleat from movement in the slightest degree, this result being obtained by the elongated shape of the cleat and the fact that it is secured by a plurality of nails, as distinguished from the use of a metal cap that receives only one nail so that by using 35 my cleats a two to one multiple of safety is provided against leaks being caused by nails going into cracks or crevices in or between sheathing boards.

35 The raised portion of the cleat being not wider than the face of such a hammer as is ordinarily used in driving the nails there is no crushing down of the crown between the side walls and the crown of the arch being practically no wider than the head of the nail being driven through it therefore presents no surface beyond the head of the nail for the face of a hammer to come into contact with when the blow is not accurately delivered, so that the impact of the blow is 40 always caught by the head of the nail and the pressure distributed evenly throughout the cleat at the base flange. Missing the nail entirely, the hammer would be apt to hit, not the side, but the base flange.

45 It is to be particularly noted that my

cleat being arched transversely and having a narrow crown and having its side walls extending abruptly from the crown, there is thereby produced a construction in which there is a high degree of resistance to avoid 70 possibility of the cleat being mashed when nails are driven through it, and furthermore, due to this construction, there is no opportunity for the crown of the cleat being depressed between the side walls, but, on the contrary, force that is applied to the crown must be transmitted directly therefrom through the side walls to the object on which the cleat is laid. It is further to be noted in connection with the features of 75 construction set forth, that the end portions of the cleat serve as stays for the side walls to prevent their outward movement or spreading action, thereby greatly increasing 80 the rigidity of the cleat, in order that it may 85 perform its office with a high degree of efficiency. I desire to call attention, in connection with the last mentioned feature of construction of my cleat, to the fact that the end or stay portions of the cleat are produced by drawing the metal at the ends of 90 the cleat, as distinguished from a mere bending action, and that, as a consequence, the metal in the end portions is caused to become set and to stiffen due to the drawing 95 of the metal. The end portions are, therefore, rendered of such nature as to offer greater resistance to the outward movement or spreading of the side walls than they would if the metal was not drawn as stated. 100

I claim:—

1. A cleat arched transversely and having greater length than breadth, the crown of the arch being narrow, the side walls of the arch leading with sufficient abruptness from the narrow crown to the base of the cleat to prevent depression of the crown between the side walls, and the ends of the cleat being closed by stay portions restraining the side walls from spreading outwardly beneath 105 said crown.

2. A cleat arched transversely and having greater length than breadth, the crown of the arch being narrow, the side walls of the arch leading with sufficient abruptness from the narrow crown to the base of the cleat to prevent depression of the crown between the side walls, the ends of the cleat being closed by stay portions drawn from, and leading abruptly from, the crown to the base of the cleat and connecting the side walls to resist outward movement thereof beneath the 115 crown of the cleat.

3. A cleat arched transversely and having greater length than breadth, the crown of the arch being narrow, the side walls of the arch leading with sufficient abruptness from the narrow crown to the base of the cleat to prevent depression of the crown between 120 the side walls, and the ends of the cleat be- 125

ing closed by stay portions restraining the side walls from spreading outwardly beneath said crown; the crown of said arch having therein, in alinement with each other longitudinally of the cleat a plurality of nail holes at the transverse center of the crown for a plurality of nails collectively of service in holding the cleat to its seat by direct action therefrom to and through said

10 side walls.

4. A cleat arched transversely and having greater length than breadth, the crown of the arch being narrow, the side walls of the arch leading with sufficient abruptness from

15 the narrow crown to the base of the cleat to prevent depression of the crown between the

side walls, the ends of the cleat being closed by stay portions leading abruptly from the crown to the base of the cleat and connecting the side walls to resist outward movement thereof beneath the crown of the cleat; the crown of said arch having therein, in alinement with each other longitudinally of the cleat a plurality of nail holes at the transverse center of the crown for a plurality of nails collectively of service in holding the cleat to its seat by direct action therefrom to and through said side walls.

20 25 WILLIAM H. WOERHEIDE.
